UNITED STATES PATENT OFFICE

ADELE G. WEATHERLY, OF MINNEAPOLIS, MINNESOTA

SLIP

Application filed November 12, 1928. Serial No. 318,782.

My invention relates to an improvement in slips for ladies such as are worn underneath the outer dress, and my design is of such a nature that it may be worn readily 5 under a thin dress and yet not detract from the lines of a slender figure or formation and design of the outer dress. These features are important because my slip is designed to provide a freedom of the body, overcoming 10 many of the disadvantages of close or tight fitting under-slips which have been made heretofore for ladies and girls.

A feature of my slip is to provide a freedom in the sides of the same so that when 15 sitting the slip will not creep up or bind and be uncomfortable to the wearer. The design of my slip is to provide the desired freedom at the sides of the same which will overcome tearing yet maintaining a close fit 20 about the body and it being virtually impossible to tear the skirt of the slip in ordinary movement of the body.

It is also a feature of my invention to provide a slip of a design and nature wherein 25 the same will fit over the body, remaining in perfect place at all times under any conditions, and overcoming any bundlesome or surplus bunching at the sides of the garment where a garment of this nature is made with 30 sufficient fullness for freedom of action by the wearer. In a garment of this nature it is very desirable to maintain slender lines whether one's figure is slender or more developed, and by a peculiar construction and 35 arrangement of the parts I provide in a very simple manner a slip of this nature, giving all of the advantages most desired by ladies and girls wearing slips of this nature beneath the regular dress, yet I maintain a slip 40 wherein comfort is assured to the wearer and permitting walking with freedom and without fear or danger of tearing or binding of the slip about the limbs of the wearer.

The design of my slip is such as to cause 45 the same to permit freedom and comfort to the wearer and also providing the important feature of having the skirt of the slip give a very unusual freedom to the sides of the same without bunching or puckering over the hip line and wherein the skirt will assume a

natural close fit to the body almost automatically when the wearer stands erect. This maintains the slender lines so desired in costumes and fashions of this time.

These features and objects of the invention, 55 together with other details and advantages will be more fully and clearly set forth in the specification and claims.

In the drawing:

Figure 1 shows my slip or under-garment 60 as it would appear in use.

Figure 2 is a back view of the same.

Figure 3 is a section on the line 3--3 of Figure 2.

Figure 4 illustrates the back portion of the 65 garment separated from the front portion.

Figure 5 illustrates the front portion separated from the back portion.

In the drawing my slip or under-garment A is designed to fit the wearer with the intention of providing a slender and neat figure and wherein freedom to the movement of the hips and sides is afforded the wearer without having the usual undesirable bunching or tucking at the sides which is objectionable 70 and unsightly where ordinarily slips are worn beneath the dress.

A feature of my slip is the simple design wherein the slip is made up of two main parts, namely, the front 10 and the back portion 11. In Figures 4 and 5 I show virtually 80 the geometric development of the front and back portions 10 and 11. In Figure 5 the formation and shape of the cut-out front portion 10 is illustrated by the dotted lines, while 85 in full lines I illustrate the front portion after it has been gathered to shape the same.

The front and back portions 10 and 11 are formed straight with straight sides and are adapted to be connected together in a very 90 simple manner. The front 10 is provided with an upper portion 12 which forms the trunk part of the slip when attached to the upper trunk portion 13 of the back 11. These 95 two portions 12 and 13 are secured together along the edges 14 so as to attach these two members 12 and 13 together in a seam which extends virtually along under the arm, such as the seam 15, illustrated in the garment A 100

in Figure 1. This seam extends along to the hip line 16 of the garment A.

Each of the portions 10 and 11 are formed with skirt portions 17 and 18, respectively, and it will be noted that the skirt portion of the front 10 is wider than the skirt portion 18. In fact, the skirt portion 18 of the portion 11 is virtually of the same width as the trunk portion 13, forming a straight panel 10 for the back portion 11. The skirt portion 18 is provided with suitable lace 19 along the sides and bottom edges, or other trimming, as may be desired.

The skirt portion 17 is also provided with lace or trimming, such as 20, extending along the bottom and the sides, and it will be noted that before the skirt portion 17 is tucked in at 21 the skirt is virtually rectangular as indicated by the dotted outline projecting beyond the side edges of the skirt 17, as illustrated in Figure 5. In forming the tucking 21 the front portion 10 is cut at 22 so as to permit the tucking 21 to extend into the body of the front portion 10 sufficiently to evenly 25 tuck the edge before it is attached to the back portion 11 of the garment A. A slight tucking is also placed at 23 in the front along the top edge of the front 10 of the garment A. This gives the proper fit of the garment over 30 the bust of the wearer.

The front 10 is formed with the hip overskirt portions 24 which extend on either side of the panel-like trunk portion 12, of the front 10. When the portions 10 and 11 are attached together along the edges 14 to form the seams 15 on either side of the trunk portion of the garment, the upper edge of the hip overskirts 24 of the skirt 17 has the tucking or edge 21 attached to the back portion along 40 the hip line, illustrated by the dotted lines 26 in Figure 4 of the drawing. When the front and back portions are attached together along these lines 26, they form the attachment along the hip line 16, as illustrated 45 in Figures 1 and 2. Thus the upper edge of the skirt 17 which projects beyond the trunk or panel portion 12 is attached to the back along the hip line 16 so that the side flaps 24 overlap the back portion of the skirt 18, 50 as illustrated in Figure 2.

This forms the garment A as illustrated in Figures 1 and 2 and by means of suitable lace 27 along the top of the trunk portion, together with the shoulder straps 28, the garment is made in finished form. The sewing and putting together of the garment A is very simple as will be clearly understood, as heretofore pointed out, making a garment of a simple nature which can be easily sewed together, yet providing a very effective overlapping portion at the hips by the flaps 24 which extend over the skirt 18, as illustrated in Figure 2, far enough so as to prevent any gapping at the sides of the skirt when a considerable stride or movement of the body is

made in wearing this slip. This is very important because it gives freeness to the wearer, overcomes tearing, and prevents creeping up of the garment in sitting down.

The overlapping of the side flaps 24 will be more clearly illustrated in Figure 3 wherein it is shown that the flap or side flaps 24 of the skirt 17 overlap the back portion sufficiently so that even when the wearer is sitting or in various positions of the body, or in walking, or in moving about, the overlap of the flaps 24 with the skirt portion 18 is sufficient so that almost automatically when the figure of the wearer becomes erect the skirt portions 17 and 18 will fall into straight line with the trunk portion formed by the members 12 and 13, the flaps 24 falling straight in line with the upper trunk portion of the garment A and thus forming slender lines, overcoming any bundlesome or bunched nature over the hips and providing a garment with full freeness to the wearer, comfortable and not of a nature to spoil the appearance of the outer garment even though the outer garment may be of a thin or soft nature, thereby providing a feature of a very desirable nature to a slip or garment of this kind.

I have illustrated a particular construction and formation of my garment in accordance with the patent statutes but I desire to have it understood that variations and obvious changes may be made within the scope of the following claims without departing from the spirit of the invention.

I claim:

1. A lady's under-slip garment comprising, a two-piece member formed with front and back panel portions, said back panel portion having a comparatively straight panel-like formation from end to end and said front portion formed with projecting skirt hip flaps on either side of the skirt portion of said slip, each of said portions being secured together with a longitudinal seam from the upper edge to the hip line and the hip flaps of the front portion being gathered along the hip line transversely of the garment and attached along the hip line transversely of the back portion to cause the hip flaps to overlie the skirt of the back portion and hang straight longitudinally therewith.

2. An under-slip for a lady's garment including, front and back portions having panel formation, said back portion being of a straight panel formation from end to end, said front portion being formed with outwardly projecting hip flaps, said front and back portions being secured together longitudinally of the trunk portion and gathered and secured together transversely along the hip portions to form a non-gapping side slit skirt in sitting or standing position.

3. A slip-on undergarment including, two members providing the front and back por-

tions of said garment, said back portion being of a straight panel design, said front portion forming a comparatively straight upper panel portion with said back portion and secured thereto, and having a skirt portion with integral side flaps which are sewed to said back portion transversely along the hip line to form overlapping side skirt flaps at the hip of the garment which are rigidly secured along the hip line.
